[57] **CLAIM**

The ornamental design for a packaging container for a zipper, substantially as shown and described.

DESCRIPTION

FIG. 1 is a front isometric view of a packaging container for a zipper showing our new design;

FIG. 2 is a top plan view thereof;

FIG. 3 is a front isometric view of the exterior case of the packaging container;

FIG. 4 is a rear isometric view thereof;

FIG. 5 is a top plan view thereof;

FIG. 6 is a front isometric view of a modified form of the exterior case;

FIG. 7 is a rear isometric view thereof;

FIG. 8 is a top plan view thereof;

FIG. 9 is a front isometric view of the insert for either case;

FIG. 10 is a rear isometric view thereof;

FIG. 11 is a cross-sectional view taken on the line 11—11 of FIG. 9; and

FIG. 12 is a cross-sectional view taken on the line 12—12 of FIG. 9.
